INK DISTRIBUTION FOR HIGH-SPEED
ROTARY PRINTING PRESSES

Joseph E. Meyer and Hans J. Luehrs, Westerly,
R. I., assignors to C. B. Cottrell & Sons Company,
Westerly, R. I., a corporation of Delaware

Application October 19, 1950, Serial No. 191,012

9 Claims. (Cl. 101—350)

1

This invention is directed to ink distributions for high speed rotary printing presses, which distributions are well adapted for feeding heat dry inks of various viscosities, tack and pigment contents to the plate cylinders of multi-color high speed rotary printing presses.

One object of this invention is to provide novel and efficient means for applying to the plate cylinders inks of the required characteristics for multi-color printing in the proper quantities and to assure efficient trapping as successive colors are applied.

Another object is to provide means for controlling the several ductor mechanisms to prevent ghosting and to supply a uniform film of ink to the web, void of saturated and/or starved ink areas caused by conventional ductor mechanisms.

Another object is to provide means for controlling the ink applied to the plate cylinders by the form rolls of the ink distribution, whereby a gradual inking of the plates is assured as they pass successive form rolls.

Another object is to provide an ink distribution composed of a low speed fountain roll, a group of intermediate speed distribution rolls, two groups of high speed distribution rolls, a timed ductor means for transferring a quantity-controlled uniform supply of ink from the fountain roll to the group of intermediate speed rolls, a timed ductor means for transferring a quantity-controlled supply of ink from the group of intermediate speed rolls to one group of high speed rolls to be applied to a plate cylinder, and another timed ductor means for transferring a quantity-controlled supply of ink from the group of intermediate speed rolls to the second group of high speed rolls to be applied to the said plate cylinder; said second group of high speed rolls, when desired, being used to transfer excess ink from the plate cylinder to the group of intermediate speed rolls.

A practical embodiment of this invention is represented in connection with a four color high speed rotary printing press.

Fig. 1 represents a detail horizontal section of the printing press illustrating the ink distribution for one of the plate cylinders.

Fig. 2 represents, in diagram, a detail vertical section of the press.

Fig. 3 represents a detail vertical section of the drive showing the impression cylinder and its four plate cylinders, the drive therefor and a portion of the drive for one of the ink distributions.

Fig. 4 represents a detail section taken in the plane of the line IV—IV of Fig. 1, looking in the direction of the arrows.

2

Fig. 5 represents a detail section taken in the plane of the line V—V of Fig. 1, looking in the direction of the arrows.

Fig. 6 represents a detail section through the reduction gear, taken in the plane of the line VI—VI of Fig. 1, looking in the direction of the arrows.

Fig. 7 represents a detail section taken in the plane of the line VII—VII of Fig. 1, looking in the direction of the arrows, showing a cam for oscillating the ductor roll which works between the intermediate speed group and the upper high speed group of rolls.

Fig. 8 represents a detail section taken in the plane of the line VIII—VIII of Fig. 1, looking in the direction of the arrows, showing the cam for oscillating the ductor roll which works between the intermediate speed group and the lower high speed group of rolls.

Fig. 9 represents a detail side view of the cam for oscillating the ductor roll which works between the fountain roll and the group of intermediate speed rolls.

Fig. 10 represents a detail side view showing the housings for the means for actuating the vibrator rolls of the three groups of intermediate and high speed rolls and also showing the cam for controlling the timed oscillations of the ductor roll for the group of intermediate speed rolls.

Fig. 11 represents a detail section showing a means for actuating a vibrator roll.

In the embodiment shown herein, the four plate cylinders are denoted by 1, 2, 3, 4 and their common impression cylinder by 5, the plate cylinders 35 being adapted to print the colors in the following order: yellow, red, blue and black, it being well known that the yellow color is the tackiest, the red and blue colors are less tacky and the black color is the least tacky.

The ink distributions for the several plate cylinders are alike and, therefore, a specific description of one only of the ink distributions will follow: i. e., the distribution for the plate cylinder 4.

The ink fountain is denoted by 6 and its low speed fountain roll by 7.

The group of intermediate speed distribution rolls is herein shown as comprising the vibrator roll 8, the composition roll 9 and the vibrator roll 10.

The first group of high speed distribution rolls is herein shown as comprising the vibrator roll 11, the composition roll 12, the vibrator roll 13 and its pair of form rolls 14, 15, which contact the plate cylinder 4.

The second group of high speed distribution rolls is shown as comprising the vibrator roll 16,

the composition roll 17, the vibrator roll 18 and its pair of form rolls 19, 20, which also contact the plate cylinder 4.

A timed ductor roll 21 is provided for transferring a quantity-controlled uniform supply of ink from the fountain roll 7 to the first vibrator roll 8 of the group of intermediate speed rolls.

A second timed ductor roll 22 is provided for transferring a quantity-controlled supply of ink from the second vibrator roll 10 of the group of intermediate speed rolls to the first vibrator roll 11 of the first group of high speed rolls.

A third timed ductor roll 23 is provided for transferring a quantity-controlled supply of ink from the said first vibrator roll 8 of the group of intermediate speed rolls to the first vibrator roll 16 of the second group of high speed rolls or vice versa as the conditions require.

It will be understood that the ductor rolls 22 and 23, for transferring the ink from the group of intermediate speed rolls to the first and second groups of high speed rolls, are adjusted to act in timed relationship to the ductor roll 21, which transfers the ink from the fountain roll 7 to the group of intermediate speed rolls.

The means which I have shown for driving the several elements of the printing press and its ink distributions, are as follows:

The impression cylinder 5, and its coacting plate cylinders 1, 2, 3, 4 are shown as being driven at the desired high surface speed from the main drive shaft 24 through the beveled gears 25, 26, shaft 27, pinion 28, impression cylinder gear 29 and plate cylinder gears 30, 31, 32, 33.

The ink distribution is shown as being driven from the main drive shaft 24 through the beveled gears 34, 35, shaft 36, double sprocket 37, double sprocket chain 38, double sprocket 39 and its disengageable clutch connection 40 with the shaft 41.

This shaft 41 is provided with a gear 42 which drives the two vibrator rolls 8 and 10 of the group of intermediate speed rolls at approximately one half the surface speed of the impression and plate cylinders, through the train of gears 43, 44, 45, 46, 47, 48. The gear 47 in coaction with the gears 49, 50, 51, 52 drives the vibrator rolls 11, 13 of the first group of high speed rolls at the same surface speed as the impression and plate cylinders. The vibrator rolls 16, 18 of the second group of high speed rolls are driven through the gears 49, 53, 54, 55 at the same surface speed as the impression and plate cylinders. The gear 49, rotatably mounted on a cross shaft 56, provides a reduction drive between said gear 49 and shaft 56. This reduction drive is herein shown as a planetary gearing consisting of a sun gear 57 fast to gear 49, planet gears 58, planet gear retainer 59 fast on shaft 56 and the fixed internal gear 60.

The ink fountain roll 7 is shown as driven at a low continuous speed from the shaft 56, through the train of gears 61, 62, 63, 64, 65, 66 and 67, said low speed being sufficient (with the maximum or minimum dwell of the ductor roll 21 on the fountain roll) to supply the maximum or minimum amount of ink that may be required. Additional ink supply adjustment is provided for by the usual doctor blade 68 and its adjusting screws 69.

The ductor roll 21 is actuated by means of a crank 70 fast on the shaft 56, the connecting rod 71, and lever arm 72 adjustably connected by the device 73 with the arm 74 fast on the cam shaft 75. The cams 76 fixed on the ends of the cam shaft 75 engage arms 77 adjustably connected by the devices 78 to arms 79 fast on stub shafts 80,

which carry the socket arms 81 in which the ductor roll 21 is rotatably mounted. The desired durations of the dwells of the ductor roll 21 are thus adjusted accurately by the devices 73, between their maximum and minimum limits.

The cams 82 are secured in their desired timed relation, by set screws 82*, to the ends of the shaft 56 for actuating the ductor roll 22 for the first group of high speed rolls, which cams 82 engage arms 83, adjustably connected by the devices 84, to arms 85 fast on the stub shafts 86, which carry the socket arms 87, in which the ductor roll 22 is rotatably mounted.

The cams 88 are secured in their desired timed relation, by set screws 88*, to each end of the shaft 56 adjacent the cams 82 for actuating the ductor roll 23 for the second group of high speed rolls, which cams 88 engage arms 89, adjustably connected by the device 90 to other arms 91 fast on the stub shafts 92 which carry socket arms 93, in which the ductor roll 23 is rotatably mounted.

The dwells of these ductor rolls 22, 23 may be timed with relation to the timing of the ductor roll 21 by replacing the cams 82 and 88.

The drives contained in the housings 94 for axially reciprocating the vibrator rolls may be of any well known or approved construction. One of the drives for the vibrator roll 11 for instance, is shown in Fig. 11 in which a worm 95 fast on the end of the vibrator shaft 96 meshes with a worm gear 97 fast on a shaft 98 which is rotatably mounted in a base 99 to slide axially therewith. A rock lever 100 is pivoted at 101 in the housings and its free end is eccentrically mounted on the shaft 98 whereby the rotation of the shaft 98 will cause the base 99 and shaft 98 to reciprocate together.

It will be understood that the dwell between the minimum and maximum limits of the ductor roll 21 may be adjusted by the cam adjusting device 73. This may be augmented by adjusting the screws 69 which act upon the fountain blade 68, to obtain the desired supply of ink to the ductor according to the tackiness of the ink and the area to be printed.

In operation: when a light ink, as black, is used, only a thin film can be carried to obtain adhesion to the rolls at high speeds. Therefore, all the rolls should be used to supply the proper amount of ink for obtaining clean solid printing. Under these conditions, the durations of the dwells of the ductor rolls 22 and 23 should be chosen to supply an equal amount of ink through the two groups of high speed rolls to the two pairs of form rolls, 14, 15 and 19, 20.

When medium-bodied inks, as blue and red are used, these inks being tackier than the light ink, a thicker film should be carried to obtain color strength, but to obtain clean printing a final wiping on the plates is also desirable. This can be accomplished by arranging the durations of the dwells of the ductor rolls 22, 23 so that the form rolls 14, 15 of the first group of high speed rolls will supply most of the required ink, while the form rolls 19, 20 of the second group of high speed rolls serve as wipers to condition the plates for perfect trapping combined with good color strength. These ink supply controlling devices furthermore minimize plate design repeats on the printed matter, due to sequential revolutions of the last form roll 20, which manifest themselves if the form roll 20 carries excessive ink, as is the case with conventional distributions. With heavy bodied, tacky inks as yellow for instance, the problem of ink accumulation on the rolls presents

itself. This problem can be avoided by prolonging the dwell of the ductor roll 22 on vibrator roll 10 to the extent that practically all of the ink supplied by the ductor roll 21 from the fountain to the group of intermediate speed rolls, is taken from said group to be fed through the first group of high speed rolls to the plate cylinder by the form rolls 14, 15. This condition will starve the second group of high speed rolls. Consequently the surplus ink deposited on the plate cylinder by the form rolls 14, 15 of the first group of high speed rolls will be taken off the plate cylinder by the form rolls 19, 20 of the second group of high speed rolls to be returned to the starved group of intermediate speed rolls before a fresh supply is provided therefor by the next duct of the ductor roll 21 from the fountain roll to said group of intermediate speed rolls. It follows that, under these conditions, the accumulation of surplus ink is substantially minimized.

While a continuous speed fountain roll has been herein shown and described, we do not wish to be necessarily limited to such a drive.

It is evident that various changes may be resorted to in the construction, form and arrangement of the several parts without departing from the spirit and scope of our invention; hence we do not intend to be limited to the particular embodiments herein shown and described.

What we claim is:

1. In a high speed rotary printing press, an impression cylinder, a plate cylinder and an ink distribution therefor comprising, a fountain roll, two groups of high speed rolls, a group of intermediate speed rolls, an independently timed ductor roll for supplying a quantity-controlled supply of ink from the fountain roll to the group of intermediate speed rolls, a second independently timed ductor roll for supplying most of the ink from the group of intermediate speed rolls to one of the groups of high speed rolls to be transferred to the plate cylinder, and a third independently timed ductor roll for transferring surplus ink removed from the plate cylinder through the second group of high speed rolls, to the group of intermediate speed rolls.

2. In a high speed rotary printing press, an impression cylinder, a plate cylinder and an ink distribution therefor comprising, a low speed fountain roll, two groups of high speed rolls, each group including one or more form rolls, a group of intermediate speed rolls, an independently timed first ductor roll for transferring a quantity-controlled supply of ink from the fountain roll to the group of intermediate speed rolls, an independently timed second ductor roll for transferring a quantity-controlled supply of ink from the group of intermediate speed rolls to one group of high speed rolls, and an independently timed third ductor roll for transferring a quantity-controlled supply of ink from the group of intermediate speed rolls to the other group of high speed rolls.

3. In a high speed rotary printing press, an impression cylinder, a plate cylinder and an ink distribution therefor comprising, a low speed fountain roll, two groups of high speed rolls, each group including one or more form rolls, a group of intermediate speed rolls, an independently timed first ductor roll for transferring a quantity-controlled supply of ink from the fountain roll to the group of intermediate speed rolls, an independently timed second ductor roll for transferring a quantity-controlled supply of ink from the group of intermediate speed rolls to one group

of high speed rolls, and an independently timed third ductor roll for transferring a quantity-controlled supply of ink from the group of intermediate speed rolls to the other group of high speed rolls, said other group of high speed rolls serving to return an excess supply of ink from the plate cylinder to the group of intermediate speed rolls through said third ductor roll.

4. In a high speed rotary printing press, an impression cylinder, a plate cylinder and an ink distribution therefor comprising, a low speed fountain roll, a first group of high speed rolls including one or more form rolls, a second group of high speed rolls including one or more form rolls, a group of intermediate speed rolls, an independently timed first ductor roll for transferring a quantity-controlled supply of ink from the fountain roll to the group of intermediate speed rolls, an independently timed second ductor roll for transferring a quantity-controlled supply of ink from the group of intermediate speed rolls to the first group of high speed rolls, and an independently timed third ductor roll for transferring a quantity-controlled supply of ink from the group of intermediate speed rolls to the second group of high speed rolls.

5. In a high speed rotary printing press, an impression cylinder, a plate cylinder and an ink distribution therefor comprising, a low speed fountain roll, a first group of high speed rolls including one or more form rolls, a second group of high speed rolls including one or more form rolls, a group of intermediate speed rolls, an independently timed first ductor roll for transferring a quantity-controlled supply of ink from the fountain roll to the group of intermediate speed rolls, an independently timed second ductor roll for transferring a quantity-controlled supply of ink from the group of intermediate speed rolls to the first group of high speed rolls, and an independently timed third ductor roll for transferring a quantity-controlled supply of ink from the group of intermediate speed rolls to the second group of high speed rolls serving to return an excess supply of ink from the plate cylinder to the group of intermediate speed rolls through said third ductor roll.

6. In a high speed rotary printing press, an impression cylinder, a plate cylinder and an ink distribution therefor comprising, a low speed fountain roll, two groups of high speed rolls, each group including vibrator and form rolls, a group of intermediate speed rolls including vibrator rolls, an independently timed first ductor roll for transferring a quantity-controlled supply of ink from the fountain roll to a vibrator roll of the group of intermediate speed rolls, an independently timed second ductor roll for transferring a quantity-controlled supply of ink from another vibrator roll of the group of intermediate speed rolls to a vibrator roll of one group of high speed rolls, and an independently timed third ductor roll for transferring a quantity-controlled supply of ink from said first named vibrator roll of the group of intermediate speed rolls to a vibrator roll of the other group of high speed rolls.

7. In a high speed rotary printing press, an impression cylinder, a plate cylinder and an ink distribution therefor comprising, a low speed fountain roll, two groups of high speed rolls, each group including vibrator and form rolls, a group of intermediate speed rolls including vibrator rolls, an independently timed first ductor roll for transferring a quantity-controlled supply of ink from the fountain roll to a vibrator roll of the

group of intermediate speed rolls, an independently timed second ductor roll for transferring a quantity-controlled supply of ink from another vibrator roll of the group of intermediate speed rolls to a vibrator roll of one group of high speed rolls, and an independently timed third ductor roll for transferring a quantity-controlled supply of ink from said first named vibrator roll of the group of intermediate speed rolls to a vibrator roll of the other group of high speed rolls, said other group of high speed rolls serving to return an excess supply of ink from the plate cylinder to the group of intermediate speed rolls through said third ductor roll.

8. In a high speed rotary printing press, an impression cylinder, a plate cylinder and an ink distribution therefor comprising, a low speed fountain roll, a first group of high speed rolls including vibrator and form rolls, a second group of high speed rolls including vibrator and form rolls, a group of intermediate speed rolls including first and second vibrator rolls, an independently timed first ductor roll for transferring a quantity-controlled supply of ink from the fountain roll to the first vibrator roll of the group of intermediate speed rolls, an independently timed second ductor roll for transferring a quantity-controlled supply of ink from the second vibrator roll of the group of intermediate speed rolls to a vibrator roll of the first group of high speed rolls, and an independently timed third ductor roll for transferring a quantity-controlled supply of ink from the first vibrator roll of the group of intermediate speed rolls to a vibrator roll of the second group of high speed rolls.

9. In a high speed rotary printing press, an impression cylinder, a plate cylinder and an ink distribution therefor comprising, a low speed fountain roll, a first group of high speed rolls including vibrator and form rolls, a second group

5
10
15
20

of high speed rolls including vibrator and form rolls, a group of intermediate speed rolls including first and second vibrator rolls, an independently timed first ductor roll for transferring a quantity-controlled supply of ink from the fountain roll to the first vibrator roll of the group of intermediate speed rolls, an independently timed second ductor roll for transferring a quantity-controlled supply of ink from the second vibrator roll of the group of intermediate speed rolls to a vibrator roll of the first group of high speed rolls, and an independently timed third ductor roll for transferring a quantity-controlled supply of ink from the first vibrator roll of the group of intermediate speed rolls to a vibrator roll of the second group of high speed rolls, said second group of high speed rolls serving to return an excess supply of ink on the plate cylinder to the group of intermediate speed rolls through said third ductor roll.
